FACIAL MASSAGING DEVICE

Filed May 19, 1936

Emile Stranszky

INVENTOR.

UNITED STATES PATENT OFFICE

100,481

DESIGN FOR A FACIAL MASSAGING DEVICE

Emil Stranszky, Erie, Pa.

Application May 19, 1936, Serial No. 62,729

Term of patent 3½ years

To all whom it may concern:

Be it known that I, Emil Stranszky, a citizen of the United States, residing at Erie, in the county of Erie and the State of Pennsylvania, have invented a new, original, and ornamental Design for a Facial Massaging Device, of which the following is the specification, reference being had to the accompanying drawing, forming part thereof.

The figure is a perspective view of a facial massaging device, showing my new design.

I claim:

The ornamental design for a facial massaging device, as shown.

EMIL STRANSZKY.
